UNITED STATES PATENT OFFICE

ALAN D. DAUCH, OF PITTSBURGH, PENNSYLVANIA, AND JOSEPH SANDBERG, OF DETROIT, MICHIGAN, ASSIGNEES TO GEORGE J. HAGAN COMPANY, OF PITTSBURGH, PENNSYLVANIA, A CORPORATION OF PENNSYLVANIA

CARBURIZING AND ANNEALING FURNACE

Application filed December 11, 1928. Serial No. 325,372.

This invention relates to carburizing and annealing furnaces, and more particularly to multiple chamber double row types of counterflow regenerative carburizing or annealing furnaces in which the material is conveyed through the furnace chamber by pusher mechanisms and in which alternate rows of material are moved in opposite directions through a preheating and cooling zone 10 in which a heat exchange is effected by radiation and convection as the cold material in its travel toward the heating zone passes adjacent a row of hot material travelling in the opposite direction.

15 It is among the objects of this invention to generally improve the furnace structure to secure economy in the use of heat and reduce the time for treating the articles.

Another object of the invention is to reduce the heat losses in furnaces of this kind by providing doors on both the charge and discharge end to prevent through drafts.

Another object of the invention is to provide for automatic operation of the doors in conjunction with the operation of the pusher mechanism for feeding the material through the furnace.

Another object of the invention is to provide a furnace structure in which the heat exchange between the heated and cool articles passing out of and into the furnace is highly efficient.

Another object of the invention is to provide for independent regulation of temperature in the several heating chambers and for controlling the temperature at different portions of the individual chambers.

Another object of the invention is to provide a furnace of the above designated character which shall operate on definite time and temperature cycles under complete automatic control.

Still another object of the invention is to provide for rapidly discharging the material from the furnaces to reduce the time at which the doors are open to a minimum.

These and other objects of the invention will become more apparent from consideration of the accompanying drawings in which like reference characters designate like parts

and in which Fig. 1 is a horizontal sectional view of a furnace structure embodying the principle of this invention; Fig. 2 is a diagrammatic view illustrating the distribution of heating elements employed in the heat chambers of the furnace; Fig. 3 is a cross-sectional view of the furnace taken along the line III—III of Fig. 1; Fig. 4 is a similar view taken along the line IV—IV of Fig. 1; Fig. 5 is a sectional view of the charging end of the furnace taken along the longitudinal center line thereof; Figure 6 is a similar view of the discharge end of the furnace; Fig. 7 is a schematic view and wiring diagram of the door operating and pusher mechanism control; and Fig. 8 is a wiring diagram of the temperature control and regulating circuit.

Referring to Figures 1 to 6 inclusive of the drawings, the structure therein illustrated comprises a furnace having side and end walls 1 and 2 respectively divided into a plurality of chambers as follows: A wall 3 extending through the longitudinal axis of the furnace divides it into two furnace chambers which are again divided into separate heating chambers 4 by longitudinal walls 5 which terminate in flanged ends 5' constituting partition members to form a common chamber for the two rows to facilitate heat exchange between the hot and cold material. Pilasters 7 extend from the end walls to substantially the center of the chamber 6 for the purpose of preventing longitudinal circulation of heated air in the chamber 6. The pilasters 7 function to effect a transverse circulation of heat from the side extremities of the preheating and cooling chambers to efficiently exchange heat between heated material passing out of the furnace and cold material entering the same. The bottom of the furnace is provided with piers 8 which are more clearly shown in Figures 5 and 6 of the drawings, these piers constituting spaced supports for a roller track 9 upon which the articles to be treated or boxes in which they are contained are conveyed through the furnace upon rollers 10. The spaced relation of the piers 8 provides for efficient circulation of heat throughout the

furnace chamber. In the furnace structure illustrated in Fig. 1, there are 4 rows of piers constituting four separate conveyor supports that extend longitudinally of the furnace.

At the ends of the rows the furnace is provided with charge and discharge openings 13 and 14 respectively, which are controlled by doors 15. These doors, as shown in Figures 5 and 6, are operated through a motor drive comprising a motor 16, a suitable reduction gear and a chain hoist 17, the latter passing over sheave wheels 18 and guide pulleys 19 to obtain a direct pull on the door 15. The door operating motors 16 are provided with a magnetic brake which is schematically shown at 20 in Figure 7 of the drawings, this brake functioning to secure quick stopping of the motor when the door has reached the stop positions in its travel.

The material is conveyed through the furnace by pusher mechanism generally designated at 21, Fig. 7, which comprises a ram element 22 that engages the material or containers and pushes it on the roll conveyor from the charge to the discharge end of the furnace.

For the purpose of securing a rapid discharge of the material from the furnace chamber, the roll conveyor is inclined as shown at 23, the degree of inclination being determined by the speed at which it is desired to discharge the material. By so inclining the roll conveyor the boxes containing the treated materials require a minimum time for passing through the outlet passage of the furnace and consequently the door is opened for a minimum time, thus reducing the loss of heat. As shown in Fig. 6, the roll conveyor frame 23 may be adjusted to various inclinations by supporting it on a standard 24 having fastening means, such as notches or openings 25 for receiving a pin 26 projecting through the frame, this pin 26 being adapted to be placed in different openings 25 to vary the inclination of the conveyor.

Again referring to Fig. 1 of the drawings, the individual heating chamber 4 is divided into two zones which are adapted to maintain different temperatures, the one zone which is near the charging end of the furnace being provided with side wall heating elements 30, Fig. 2, and a bottom element 31, this zone constituting the heating up zone, and the other heating zone is provided with side wall elements 32 and no bottom element, this zone being the soaking zone of the chamber. In a carburizing process it is desirable to reduce the heating up time to a minimum and by setting the temperature in the heating up zone at a higher value than is desired in the product, the rate of heat absorption is accelerated. The rate of travel of the product through the heating up zone and the ac-

tual temperature in this zone are so adjusted that the temperature of the product is substantially at the desired value when the product enters the soaking zone which is, as hereinbefore stated, held at the temperature desired in the product. 70

It will be noted with reference to Fig. 1 of the drawings, that the heating up zone of the chambers 4 is adjacent the preheating and cooling chamber on the end of the furnace in which the material is charged and the soaking zone is adjacent the preheating and cooling chamber located at the discharge end of the furnace. 75

To operate the furnace on definite time and temperature cycles, it is necessary to provide automatic control and temperature regulation, the latter being effected by means of the equipment illustrated in Fig. 8 of the drawings, which illustrates a plurality of thermocouples 33 which are projected through the furnace in the region of the heating elements in the heating chamber. Temperature control is effected through the thermo couples by connecting the latter in the power circuit of the resistor heating elements through a series of relays 34 which are controlled by an automatic temperature controlling device indicated at 35, numerous types of which are available for this purpose. The heating element circuit disconnects by push button stations 37 and 38 which respectively disconnect the three element and the two element zones. 90

For the purpose of controlling the heat cycle of the articles treated in the furnace, it is necessary to regulate the time during which the article passes through the preheating and cooling chamber and through the heating-up and soaking zones of the heating chamber. A time clock is employed for this purpose 100 and it functions to initiate the door operating mechanism which starts the train of events that is completed by the closing of the door. The pusher mechanism for actuating the work in moving it through the furnace is associated with the door operating mechanism in such manner that their respective functions will be coordinated. 105

This is accomplished by use of apparatus and control means, as illustrated in Figure 7 of the drawings and since the work is conveyed through the furnace at predetermined time cycles or intervals, means must be provided for initiating the operation of the conveying mechanism at predetermined intervals, such a means being illustrated as a time clock 40 having movable contacts 41 and a clock relay 42. A reversible motor 16 drives the door operating mechanism and the motor circuit is controlled by a plurality of limit switches 44, 45 and 46 that are actuated by movement of the door 15. 115

The door operating mechanism is electrically interlocked with the charger mechanism, the latter being operated by a reversible 120

motor 50 which is controlled by a solenoid brake 51. The charger motor 50 is controlled by limit switches 52 and 53 which are in circuit with the limit switches of the door mechanism and the motors 16 and 50 are respectively provided with motor starters and interlocks generally designated at 54 and 55 respectively.

Push button switches 56 and 57, 58 and 59, are provided for manually controlling the circuits when desired.

The operation of the furnace is as follows: The temperature controllers, as shown in Fig. 8, are set to hold the temperatures at the desired values in the respective zones, and automatic regulation of the temperature at the predetermined values is effected through the thermo-couples and the control circuit.

The time clock 40 of Figure 7 is set to operate at given intervals and when the normally closed clock contacts 41 are opened for a short interval of time, the energizing circuit for the relay 42 is opened and this relay de-energizes.

25 By the de-energization of the relay 42, a circuit is completed that extends from one side of the line L-1, through normally closed contacts 44a of the limit switch 44, closed contacts of the push button switch 56, closed contacts 42a of the de-energized relay 42, winding of the motor starter relay 60, to the line L-2. Relay 60 energizes and completes a locking circuit for itself, extending through the contacts of the interlock 60a. The energization of the relay 60 also completes the circuit for the door motor 16, which operates in a direction to raise the doors 15 of the furnace.

30 The doors 15 are stopped in their full up position by the operation of the limit switch 44 which opens the above traced circuit of the motor relay 60. The relay 60 de-energizes and opens the circuit of the motor 16, the magnetic brake 20 operating to bring the motor and doors to rest. By the operation of the limit switch 44, a circuit is completed extending from L-1, normally closed contacts of the push button switch 57, contacts 44b of the limit switch 44, normally closed contacts 52a of the charger limit switch 52, winding of the relay 61, to the line L-2. The relay 61 energizes to establish the circuit of the charger motor 50, which operates to push the charger 21 in.

35 45 When the charger reaches its fully inward position the limit switch 52 is operated to open the circuit of the relay 61, which de-energizes and opens the circuit of the charger motor 50. the magnetic break 51 operating to bring the motor and charger to rest. Another result of the operation of the limit switch 52, a circuit is completed extending from the line L-1, closed contacts of the limit switch 46, closed contacts of the push button switch 59 and through the contacts

52b of the limit switch 52. From the contacts 52b, the circuit divides, and extends through the winding of the relay 64 to line L-2. The relay 64 energizes and completes a locking circuit for itself, under control of the limit switch 46. The other circuit from the contacts 52b extends through the closed contacts 45a of the limit switch 45, winding of the relay 62' to the line L-2.

40 The relay 62 energizes to establish a circuit for the door motor 16 in the reverse direction to operate the doors downward. By the operation of the limit switch 45, the contacts 45a are opened to open the circuit of the relay 62, which de-energizes and the door motor 16 is brought to rest as previously described.

45 As another result of the operation of the limit switch 45, the contacts 45b are closed to complete a circuit extending from L-1, closed contacts of the push button switch 58, contacts 45b, the closed contacts 53a of the limit switch 53, winding of the relay 63 to the line L-2. The relay 63 energizes to complete the circuit for the charger motor 50 in the reverse direction to operate the charger 90 outwardly. The charger is stopped in its full outward position by the operation of the limit switch 53.

50 The contacts 53a of the limit switch 53 are opened to open the circuit of the relay 63 which de-energizes and the motor 50 is brought to rest as previously described. The operation of the limit switch 53 also closes the contacts 53b which completes a circuit that extends from the line L-1, contacts of the limit switch 46, contacts of the push button switch 59, contacts 64a of the relay 64 through the winding of this relay to line L-2. The above traced circuit is the previously mentioned locking circuit for this relay.

55 From the contacts 64a, a circuit extends in parallel with the relay 68, through contacts 53b of the limit switch 53, winding of the relay 62 to the line L-2. The relay 62 energizes and establishes the circuit for the motor 16, which operates to completely lower the doors 15. The doors 15 in their fully closed position operate the limit switch 46 to open the circuit of the relays 64 and 62, thus completing the cycle of operations. When the clock contacts again open, the cycle of operations is the same as just described.

60 The doors are stopped in their downward movement by the operation of the limit switch 45 which should be adjusted to stop the doors in a position which will just clear the charger head 22. The time clock is set to periodically initiate the cycle of events in accordance with the duration of the treatment desired in the product.

65 The location of the ends of the door and charger movements may be adjusted by adjusting the limit switches.

With the furnace structure herein illus-

trated and described and the heat regulation and time control effected in the manner set forth, the highest operating efficiency is obtainable. Heat economy is effected and the duration of the carbonizing treatment is reduced to a minimum. By means of automatic regulation and control herein described, uniform quality of treatment is absolutely assured and a minimum amount of labor is required for operating the furnace.

10 Furthermore, the several furnace chambers can be individually controlled to obtain a greater diversity factor whereby the demand of power is lessened during a given operating period. Since there are four separate heating chambers in the furnace with two points of control each, there are a total of eight points of control by means of which greater economy is effected than where but 15 a single point of control is employed in each individual chamber. It is also evident that all of the chambers of the furnace need not be operated simultaneously which renders such a furnace equipment much more useful where there is a great variety in the kind and quantity of manufacture.

20 By providing for the boxes being discharged from an incline, the boxes unload themselves, so to speak, and are carried by 25 gravity to a position free and clear of the discharge furnace door.

Although one embodiment of the invention has been herein illustrated and described, it will be obvious to those skilled in the art that 30 various modifications may be made in the construction and arrangement of the several parts without departing from the principles herein set forth.

We claim herein as our invention:

40 1. A furnace structure comprising in combination a plurality of passages divided into heating, preheating and cooling chambers, means for conducting material in rows moving in alternately opposed directions through 45 said passages, means for providing heat zones of different temperatures in the several heating chambers with the highest temperature zone at the end of the heating chamber which the material enters in passing through 50 the furnace, and electrically controlled means for automatically maintaining the temperatures of the respective zones at predetermined limits.

55 2. A furnace structure comprising in combination a plurality of passages divided longitudinally into heating, preheating and cooling chambers, a roll conveyor mechanism extending through said passages and supported upon pillar blocks in said furnace, 60 pusher mechanism for moving the material on said roll conveyor, and electrically controlled means including a time clock for intermittently actuating the pusher mechanism to subject the work to a predetermined 65 heat cycle.

3. A furnace structure comprising side, top and end walls forming a heating chamber, doors at the respective ends of said chamber, mechanism for conveying material through said chamber, door operating mechanism, means actuated by movement of said doors for controlling the operation of said conveying mechanism, means actuated by movement of said conveying mechanism for controlling said door operating mechanism, and an electrical control system for said door and conveyor operating mechanism including timing means for rendering said door and pusher mechanism operative on a definite time cycle.

4. A furnace structure comprising in combination a plurality of passage communicating at their respective ends to constitute regenerative chambers at each end of the passages, heating means and temperature control means for constituting said passages, heating and soaking zones with the soaking zone of one passage and the heating zone of the other passage extending to the regenerative chambers at each end of said passages, and means for conducting material in rows moving in alternately opposed directions through said passages, the material entering the heating zones of said passages and passing out of the soaking zone into the regenerative chambers at the ends of said passages.

In testimony whereof we have hereunto set our hands this 10 day of December, 1928.

ALAN D. DAUCH.
JOSEPH SANDBERG.
